CLAIM

The ornamental design for a data communication relay device, as shown and described.

DESCRIPTION

FIG. 1 is a front, top, and right side perspective view of a data communication relay device showing our new design; FIG. 2 is a front view thereof; FIG. 3 is a rear view thereof; FIG. 4 is a left side view thereof; FIG. 5 is a right side view thereof; FIG. 6 is a top view thereof; and, FIG. 7 is a bottom view thereof.

The dashed broken lines in the figures show portions of the data communication relay device that form no part of the claimed design.
